PROCESS FOR TREATING OIL SHALE

Filed Sept. 2, 1924

UNITED STATES PATENT OFFICE.

MILON J. TRUMBLE, OF LOS ANGELES, CALIFORNIA.

PROCESS FOR TREATING OIL SHALE.

Application filed September 2, 1924. Serial No. 735,355.

My invention relates to the art of treating oil shale, and is particularly applicable to the destructive distillation of oil shale by means of superheated steam.

5 It is a well known fact that oil shale, in its natural state, contains substances which can be converted into volatile hydrocarbons by the application of heat and pressure. It is an object of my invention to provide an apparatus 10 by which this conversion can be accomplished.

Further objects and advantages of the invention will be made evident hereinafter.

The annexed drawing is a diagrammatic representation partly in section of an apparatus adapted to carry on my process. In this apparatus I employ a preheater 1 which is placed in a spent shale receiver 2 and which is adapted to deliver shale into a retort 3. A dephlegmator 4 and a primary condenser 5 15 are provided, also a suction fan 6 and a secondary condenser 7.

In the form of apparatus shown, the preheater 1 consists of a tight shell 11 having a perforated top 12 and a discharge spout 13. A filling neck 14 (hereinafter referred to as means for charging) is provided with a cover 15 and the discharge spout 13 is provided with a cover 16. A shield 17 is placed above the perforations in the top 12. The spent shale receiver surrounds the preheater and consists of a shell 21 having a filling neck 22 (hereinafter referred to as means for charging) closed by a cover 23. A discharge spout 24 (hereinafter referred to as means for delivering shale from said heater to said retort) extends downwardly and is closed by a cover 25. Walls forming an air preheating chamber 26 surround the spout 24, the admission of air to the chamber 26 being controlled by 30 a valve 27. Air is taken from the top of the air chamber 26 through a plurality of pipes 28 and is discharged into the spent shale receiver through slots 29, in the pipes 28.

The retort 3 is provided with a filling neck 31 closed by a cover 32 and with a discharge spout 33 provided with a cover 34. The discharge spout 33 is so placed that it can readily discharge into a skip 35 which can be elevated as by a chain or rope 35^a connected with a bail 35^b to discharge into the filling neck 22 of the spent shale receiver 21 (and which is herein-after referred to as means for delivering spent shale from said preheater to said retort). The same skip (preferably provided with a fairly tight cover, not shown, to smother any 55 flames spontaneously produced by momentary

exposure of the hot spent shale, preferably handled above its ignition point, to the air) can be used to fill the preheater 1, if desired. The covers 32 and 34 can be made pressure-tight and superheated steam may be discharged into the interior of the retort 3 through a nozzle 36, the flow being controlled by a valve 37.

60 The dephlegmator 4 is of standard construction, containing pans 41 and 42, through and about which ascending vapors take a tortuous course. Vapor is delivered from the top of the dephlegmator 4 through a pipe 43, and condensates are removed from the bottom through a pipe 44. Vapor is delivered from the retort 3 to the dephlegmator 4 through a pipe 38.

70 The condenser 5 is of any standard type of construction. The suction fan 6 is provided with an inlet pipe 61 which extends from and connects to the discharge spout 13 of the preheater 1, vapors being discharged from the pipe 6 into the condenser 7, which is of any standard type of construction.

75 The method of operation of my invention is as follows:

The apparatus being charged with shale, the covers 32 and 34 are closed and superheated steam is delivered through the nozzle 36 into the mass of shale in the retort 3. The steam is preferably at or above 1000 degrees Fahrenheit and it acts upon the shale to raise it to a comparatively high temperature and to drive off the volatiles there-through, these volatiles passing through the pipe 38 to the dephlegmator 4, and through the pipe 43 to the condenser 5. The condensates produced is one of the commercial 80 products of the plant.

85 The preheater 1, being filled with raw shale, is given a preliminary treatment by means of hot spent shale in the spent shale receiver 2, the spent shale receiver having been charged by means of the skip 35 from the retort 3. The plate 17 prevents shale from clogging the openings 39 in the perforated top 12. The spent shale at a high temperature completely surrounds the preheater 1 and tends to produce a preliminary distillation therein. Air being delivered through the valves 27 to the air heating chamber 26 is then injected into the spent shale in the spent shale receiver 2, through the openings 29 in the pipe 28.

90 100 105 110 Spent shale ordinarily contains considerable quantities of free carbon or tar, and

by the injection of air, a combustion is set up which further elevates the temperature of the spent shale and serves to heat the pre-heater 1. The gases of combustion are also drawn under the plate 17 and through the openings 39, downwardly through the raw shale in the preheater 1, by means of the pump 6 and the pipe 61. During the passage of the hot vapors through the shale, considerable distillations take place therefrom, the products being condensed in the condenser 7.

It will be noted that my invention comprises the novel conception of utilizing the hot spent shale to preheat the raw shale before subjecting it to distillation in the retort 3. It also provides a novel conception of accomplishing this preheating partly by means of the combustion gases produced by burning out the carbonaceous matter remaining in the spent shale for distillation.

I claim as my invention:

1. In the destructive distillation of oil shale, a process which comprises: preheating the raw shale by passing hot spent shale

in heat-exchanging relationship, but out of contact with a body of the raw shale; distilling a body of the preheated shale by contacting therewith highly superheated steam; recovering volatile products thus produced; and burning residual carbon from said spent shale during the maintenance of the mentioned heat exchanging relationship.

2. In the destructive distillation of oil shale, a process which comprises: preheating the raw shale by passing hot spent shale in heat-exchanging relationship, but out of contact with a body of the raw shale; distilling a body of the preheated shale by contacting therewith highly superheated steam; recovering volatile products thus produced; and burning residual carbon from said spent shale during the maintenance of the mentioned heat exchanging relationship and passing the resultant products of combustion through said raw shale.

In testimony whereof, I have hereunto set my hand at Los Angeles, California, this 26th day of August, 1924.

MILON J. TRUMBLE.
